Claims priority, application Italy April 11, 1956

5 Claims. (Cl. 74—27)

In the field of graphic art and of book-binding, the so-called "trilateral" ("three-sided") machines are well-known. Such machines, as their name indicates, serve to cut or trim piles of books or reams of paper and the like on three sides. In this respect, the back of the book or ream is stitched or glued and, prior to applying the cover, it is necessary to trim or cut the three sides of the pile.

Such machines have three knives, one front blade and two side blades, which are moved with independent movements. In other words, the usual practice in the art recommends that the trimming at the sides should be carried out first and, then, the front trimming. This requirement obviously stems from the fact that, if front trimming were carried out first, the pile or ream might become misaligned and the operator would be compelled to square the ream again prior to carrying out the side finishing.

For the reasons now set forth, modern trilateral machines are provided with a synchronizing device permitting the descent and return of the side blades and, then, the descent and return of the front blade.

Such machines are always equipped, moreover, with a paper-pressing device that descends with a slight advance with respect to the descent of the side blades and serves the purpose of keeping the pile or ream compressed during cutting.

A carriage, which is slidable on an inclined bench, carries the pile or ream to be trimmed. When the carriage has taken the pile or ream to the cutting position, a spring mechanism becomes operative and engages a disk-clutch connected with the device for actuating the knives. The carriage is actuated manually by the operator, who makes it advance to the cutting position of the pile of books, waits for the cutting to have been completed and returns the carriage back to receive the new pile of books and so on. It is evident that such work requires the expenditure of considerable energy by the operator. For a further understanding of the operation, the normal working cycle of such conventional machines may be briefly summarized as follows:

The operator loads the pile of books on the carriage and pushes the carriage by hand as far as the cutting position at this point, the carriage releases a spring mechanism which in turn releases movement of the paper-pressing device and of the side blades. Thus, the side trimming of the pile is obtained. On termination of this trimming, the side blades rise to return to their upper dead point and come to a standstill, and the front blade becomes operative.

On having carried out the cutting, the front blade rises, returns back to its upper dead point and stops.

The blades do not function again until the carriage return at its end of travel for the introduction of another pile.

Hence, the cutting of a pile comprises the following stages.

2

- (a) Loading of the pile onto the carriage;
- (b) Feed travel of the carriage;
- (c) Cutting proper;
- (d) Discharge of cut pile;
- (e) Return travel of the carriage.

The introduction of the pile is the operation that determines the release of movement of the cutting members. Thus, it is evident that the frequency of cutting passes and, therefore, the production of trimmed piles in determined interval of time, depend on the frequency with which the operator loads the machine. As aforesaid, it is almost impossible for an operator to exert a continual effort beyond certain limits. In actual practice, it is hardly possible for an operator to trim more than six or seven piles per minute.

From the foregoing, it will be seen that there are conventional trilateral machines which are equipped with devices for actuating blades in a synchronized manner with the arrival of the carriage at the feed-end travel position. However, the feed movement of the carriage and its return travel for receiving a new pile are effected manually.

It is a main object of the present invention to provide a mechanism capable of replacing the operator for automatically carrying out the feed stage of the pile-carrying carriage and the return travel of said carriage, taking into account the intervals of time needed to load the pile at one side, to trim and to unload the finished pile at the other side.

It is another object of the present invention to provide a mechanism adapted to provide a feed path for a carriage which is slidably movable on guides, to enable stopping of said carriage during a certain predetermined length of time, to provide a return movement of said carriage and to enable halting of said carriage during a predetermined interval of time, which may be different from the first halting time duration, and to repeat cyclically the operations just recited, any number of times at will.

It is another object of the present invention to provide a mechanism capable of transforming a continuous rotary motion into a rectilinear feed motion of a slidable member, followed by a halt, by a return motion and by another halt and so on.

It is a further object of the present invention to provide a mechanism to be applied on trilateral cutting machines for trimming paper in books, blocks or reams, the mechanism being capable of forwarding the carriage carrying the pile to be trimmed to the position of cutting, of keeping it there during the cutting operation, of returning the carriage when the cutting has been terminated and of keeping the carriage at standstill during the time needed by the operator to load another pile onto the carriage.

These and other objects of the present invention will appear evident from the particular description that follows hereinafter with reference to the accompanying drawings, wherein:

Fig. 1 represents a longitudinal section of the case containing the mechanism of the invention;

Fig. 2 is a representation partly in section taken along lines B—B of Fig. 1 and showing part of the construction partly in elevation;

Fig. 3 shows how the movement of the mechanism according to the invention is transmitted to the carriage that carries the pile of books to be trimmed;

Fig. 4 represents a braking device of the star plate.

With reference to the drawings, now there will be described the device of the invention in its particulars.

An electric motor is provided for transmitting rotary movement to a pulley, as shown in Fig. 1, by means of belts. A gear is connected to the pulley and through a clutch means 80 and a suitable gearing arrangement 45

transmits rotary movement to the shaft 31 which parallels the shaft 40. The shaft 31 is disposed parallel with the shaft 5. Fixed on the shaft 31 is the plate 27, the sector gear 26 and the sector disk 25. Fixed on the shaft 5 are the star plate 24, the sector gear 23 on one side and the disk 4 with the button 10 on the other side.

By virtue of such arrangement, the continuous rotary movement of the shaft 31 is translated into a movement of intermittent rotation by the shaft 5, the shaft 5 having its rotation interrupted by two halting periods. In other words, the button 10 is provided to travel in an arc of 180°, to stop for a short period, and then travel over another arc of 180° and stop for a period of longer than that of the preceding stop. This operation is repeated cyclically.

The device providing the succession of movements of the pile-carrying carriage according to the object of the present invention, will be easily understood with particular reference to Fig. 2. With the shaft 31, as said, there are rigid the shaped plate 27, the sector gear 26 and the sector disk 25. Parallel and above with respect to the shaft 31 there is the shaft 5, whereon there are fixed the star plate 24, and the sector gear 23 on one side, and the disk 4 with button 10 on the other side. The kinematical problem to be solved is to transform the continuous rotary movement of shaft 31 into a movement of rotation interrupted by two halting periods of the shaft 5: in other words, the button 10 is wanted to travel over an arc of 180°, to stop for a short period, to travel over another arc of 180°, to stop for a period longer than that of the preceding halt, and so on repeating these operations cyclically.

On observing more particularly the shaped plate 27, it will be noted that it is composed of two parts or wings of sector shape equal to each other and the axes of symmetry whereof are radial with respect to the center of the shaft 31 and form an obtuse angle. From Fig. 2 it will be noted also that on the ends of each of the two arcs of the plate 27 there are fixed two studs. In Fig. 2 the studs are designated with 28, 28', 28'', 28'''', according to the order with which they follow one another in plate rotation.

For a more particular understanding of operations, let us suppose that the plate 27 turns in clockwise sense with respect to an observer observing the mechanism in the directions of the arrow C of Fig. 1.

The star plate 24 then will turn in an anti-clockwise sense as will be explained hereinafter; the curved arrows in Fig. 2 represent the movement mentioned just now.

Operation of the mechanism is as follows:

The stud 28 penetrates into the first eyelet of the plate 24 and pushes it in rotation. As soon as the stud 28 is going to leave the first eyelet, and this takes place when the stud 28 has surpassed in its travel the axial line that connects the centres of the shafts 5 and 31, the first toothed sector rigid with the wheel 25 engages with the corresponding toothed sector 23 rigid with the plate 24 which continues rotating. When the teeth of the toothed sectors are going to disengage, the stud 28' penetrates into the second eyelet of the plate 24 and pushes it to complete the rotation of plate 24 by 180°. From what has been stated hereinbefore, a rotation of the star plate by 180° is obtained according to the following succession of movements:

(a) Entrance of a stud (28) into an eyelet of the plate 24, with start of rotation of the plate 24;

(b) Exit of the stud (28) from the eyelet, engagement between the toothed sectors respectively rigid with the plate 27 and with the plate 24;

(c) Termination of engagement between the toothed sectors mentioned above under (b) and entrance of the subsequent stud (28') into the subsequent eyelet of the plate 24 until completion of the rotation by 180°.

On inspecting again Fig. 2, it will be seen that the free arcs between the two wings of the plate 27 are occu-

pied by the sectors H and K having smooth borders and it will also be noted that sector H is narrower than sector K.

These sectors H and K are integral with the sector disc 5 which as said is fixed to the shaft 31 coaxially with respect to the shaped plate 27 and to the sector gear 26. Attention is called here to the fact that the radius of curvature of the sectors H and K coincides with the radii of curvature of the curved portions of the star plate 24. There is a slight phase shift between the end of the rotation by 180° of the plate 24 and the beginning of the contact of the sector H with the corresponding curved portion of the plate 24. The length of time during which the sector H finds itself at contact with the corresponding curved portion of the plate 24, represents the halt of the pile-carrying carriage under the blades for trimming. Once the sector H has left the curved portion of the plate 24 mentioned above, the second wing of the shaped plate 27 comes to act, which carries the studs 28'' and 28''' and under which is placed a toothed sector equal to that provided under the first wing carrying the studs 28 and 28'. Now the succession of movements as already described is repeated, there is a new rotation by 180° of the plate 24, until the sector K comes to find itself at contact with the corresponding curved portion on the plate 24. The length of time during which the sector K is at contact with the corresponding curved portion on the plate 24, represents the halt—longer than the one corresponding to the sector H—for loading the pile of books on the carriage.

Summarizing the above, the correspondence between the movements of the mechanism described and the movement of the pile-carrying carriage can be stated to be as follows:

- 35 (A) Rotation by 180° of the star plate 24, which corresponds to the feed travel of the pile-carrying carriage;
 (B) Contact of the sector H with the curved portion of the star plate 24, which corresponds to the halt of the carriage for enabling to effect trimming and discharge 40 of the trimmed pile;
 (C) Subsequent rotation by 180° of the star plate 24, which corresponds to the return travel of the discharged carriage;

- 45 (D) Contact of the sector K with the curved portion of the star plate 24, which corresponds to the halt of the carriage for loading thereon a new pile of books to be trimmed.

It may be added that the continuous rotation of the shaft 31 ensures the cyclic repetition at will of the operations A-B-C-D, in the order of succession hereinbefore specified.

Means is then provided for transforming the continuous movement of a rotary shaft into a composite rotary movement, formed by a rotation by 180°, a short halt, a second rotation by 180° and a longer halt, of a second shaft.

Now the composite rotary movement has to be translated into the succession of movements required for the pile-carrying carriage, namely:

- 60 (1) Feed travel of the loaded carriage;
 (2) Halt for cutting and unloading of the trimmed pile;
 (3) Return travel of the empty carriage;

65 (4) Halt for loading a new pile on the carriage. To understand how the succession of the movements as set forth is obtained in practice, particular reference is made to Fig. 3. In that figure the pile-carrying carriage is visible, which has not been represented in the preceding figures.

70 The carriage is slidably mounted on guide and whereon it can slide: it will be noted from Fig. 3 that the carriage is inclined with respect to the horizontal. At the end of the carriage C nearest to the operator, that is, to the right hand of him who observes Fig. 3, there is 75 pivoted at 18 the upper end of an oscillating arm 16.

The lower end of said arm 16 is pivoted to the small adjustable connecting rod 20 and the latter is pivoted to the support 100.

The crankpin 10 is pivoted on a small adjustable connecting rod 12 and the latter in turn is pivoted on the oscillating arm 16 at a point 15. The crankpin 10 in its rotation drags along with it the arm 16. It has been seen that by virtue of the mechanism represented in Fig. 2, the crankpin 10 achieves two rotations by 180° intermeshing by pauses: the same will happen now with the carriage C since the arm 16 in oscillating also will drag along with it the carriage. Hence the latter will perform the feed travel, halt for the time necessary for cutting and unloading the trimmed pile, perform the return travel, halt for the time necessary for loading the new pile to be trimmed, and so on. Now with particular reference to Fig. 4, the braking device will be described that serves to render easier the movement of the shaft 5 whereon the star plate 24 is mounted.

It is desirable, in order to obtain a more regular movement of the shaft 5, to have the possibility of braking said shaft a short time before the sectors H and K of the disc 26 come to contact the corresponding curved portions of the star plate 24: meeting this requirement means avoiding shocks and vibrations as would be unavoidably caused otherwise, when the sectors H and K come to act, by the stopping of the star plate 24.

The requirement mentioned above is met by the device as represented in Fig. 4 and visible also in Fig. 1.

About the pin 114 there is mounted the shoe brake 112: the free end of the lever of said brake being controlled by the cam 117. Said cam is mounted on the shaft 31 and as is seen in Fig. 4, it provides two braking stages and two positions of disengagement: the duration of the stages of braking corresponding to the halting time wanted. To the lever of the brake 112 there is pivoted at 116 a tension rod 118 which is guided by the stirrup 115. The spring 118' is fitted over the tie rod 118 and rests at one end against the stirrup 115 and at its other end against a nut screwed onto the free threaded end of the tie rod 118. It is thus possible to adjust the tension of the spring at will.

The brake shoe 113 acts upon the grooved pulley 109 fitted on the shaft 5.

I claim:

1. A mechanism for automatically controlling the introduction and discharge of paper piles in a trilateral cutting machine comprising a reciprocating carriage adapted to support the paper piles, an intermittently rotating operating means, means operatively connecting the intermittently rotating operating means with the carriage to translate such intermittent rotation into intermittent reciprocatory movement of the carriage, a continuously rotating driving means and means connecting the continuously rotating driving means to the intermittently rotating operating means so as to produce the intermittent rotation thereof, said continuously rotating driving means including a rotating drive shaft, said intermittently rotating operating means including a driven shaft parallel to the drive shaft and said connecting means including a plate circumscribed on the driving shaft and formed of two sectors arranged at an obtuse angle relative to each other, said sectors having arcuate peripheral portions provided with teeth, a stud provided at the end of each peripheral portion and extending laterally from the sectors, a disc circumscribed on the drive shaft and arranged coaxially with and fixed to the plate and having two smooth sectors arranged in the spaces between and on the same radius with the toothed portions of the sectors, a star plate circumscribed on the driven shaft and having two pairs of spaced side by side eyelets on its periphery for engagement with the studs and having a curved section between the eyelets of each pair and a rectangular portion between each eyelet of one pair and each eyelet of the other pair and a disc circumscribed on the driven

shaft and arranged coaxially with and fixed to the star plate and having two toothed sectors which project beyond the rectangular portions of the star plate whereby movement is transmitted from the driving shaft to the driven shaft at first by means of the entrance of a stud of the plate into one eyelet of the star plate, to put it to rotation, then the movement is continued, when the stud leaves the eyelet, by the engagement of the corresponding toothed sectors of the plate and the star plate, then a second stud of the plate enters into a second eyelet of the star plate as seen as the toothed sectors disengage, so that a rotation by 180° of the star plate is achieved, whereafter one of the smooth sectors of the disc rigid with the plate slides in contact with one curved section of the star plate comprised between the two eyelets of one pair, until the first stud of the subsequent sector zone enters into the corresponding eyelet of the star plate, putting it to rotation again, the movement of the star plate being resumed with the engagement of two corresponding toothed sectors, then the second stud of said subsequent sector zone of the shaped plate enters into the eyelet of the star plate as soon as the toothed sectors disengage, thus obtaining a second rotation by 180° of the star plate as soon as the toothed sectors disengage, disc rigid with the plate slides in contact with the other curved section of the star plate, whereby there is obtained a movement of the star plate and, therefore, of the driven shaft, which is constituted by a rotation by 180°, a short halt, a second rotation by 180° and a longer halt, said movement being repeated cyclically by the rotation of the driving shaft.

2. A mechanism for automatically controlling the introduction and discharge of paper piles in a trilateral cutting machine comprising a reciprocating carriage adapted to support the paper piles, an intermittently rotating operating means, means operatively connecting the intermittently rotating operating means with the carriage to translate such intermittent rotation into intermittent reciprocatory movement of the carriage, a continuously rotating driving means and means connecting the continuously rotating driving means to the intermittently rotating operating means so as to produce the intermittent rotation thereof, said continuously rotating driving means including a rotating drive shaft, said intermittently rotating operating means including a driven shaft parallel to the drive shaft and said connecting means including a plate circumscribed on the driving shaft and formed of two sectors arranged at an obtuse angle relative to each other, said sectors having arcuate peripheral portions provided with teeth, a stud provided at the end of each peripheral portion and extending laterally from the sectors, a disc circumscribed on the drive shaft and arranged coaxially with and fixed to the plate and having two smooth sectors arranged in the spaces between and on the same radius with the toothed portions of the sectors, a star plate circumscribed on the driven shaft and having two pairs of spaced side by side eyelets on its periphery for engagement with the studs and having a curved section between the eyelets of each pair and a rectangular portion between each eyelet of one pair and each eyelet of the other pair and a disc circumscribed on the driven shaft and arranged coaxially with and fixed to the star plate and having two toothed sectors which project beyond the rectangular portions of the star plate whereby movement is transmitted from the driving shaft to the driven shaft at first by means of the entrance of a stud of the plate into one eyelet of the star plate, to put it to rotation, then the movement is continued, when the stud leaves the eyelet, by the engagement of the corresponding toothed sectors of the plate and the star plate, then a second stud of the plate enters into a second eyelet of the star plate as soon as the toothed sectors disengage, so that a rotation by 180° of the star plate is achieved, whereafter one of the smooth sectors of the disc rigid with the plate slides in contact with one curved section

of the star plate comprised between the two eyelets of one pair, until the first stud of the subsequent sector zone enters into the corresponding eyelets of the star plate, putting it to rotation again, the movement of the star plate being resumed with the engagement of two corresponding toothed sectors, then the second stud of said subsequent sector zone of the shaped plate enters into the eyelet of the star plate as soon as the toothed sectors disengage, thus obtaining a second rotation by 180° of the star plate, whereafter the other smooth sector of the disc rigid with the plate slides in contact with the other curved section of the star plate, whereby there is obtained a movement of the star plate and, therefore, of the driven shaft, which is constituted by a rotation by 180° , a short halt, a second rotation by 180° and a longer halt, said movement being repeated cyclically by the rotation of the driving shaft, said means connecting the intermittently rotating operating means with the carriage including a disc fixed on the driven shaft and having a crankpin and a leverage system pivoted on the crankpin and to the carriage.

3. The combination of claim 2, wherein said leverage system includes a rod fulcrumed at one end to a fixed support, an oscillating arm pivoted at its ends to the rod and to the carriage and a connecting rod pivoted to the arm intermediate the rod and the carriage and pivoted on the crankpin.

4. The combination of claim 3, wherein a braking means is provided for stopping the driven shaft in slight advance of the engagement of the smooth sectors of the disc with the curved sections of the star plate and includes a pulley fixed on the driven shaft, a lever provided with a brake shoe engageable with the periphery of the

pulley, said lever being pivoted at one end and having a free end, a cam secured on the driving shaft and on which the free end of the lever rides and a spring tension means holding the free end in engagement with the cam.

5. A mechanism for automatically controlling the introduction and discharge of paper piles in a trilateral cutting machine comprising a rectilinearly reciprocating carriage, a continuously rotating driving shaft, a plate composed on the driving shaft and having sectors arranged in circumferentially spaced relation, said sectors having teeth arranged along their peripheral portions and having studs outstanding laterally from the ends of said peripheral portions and means providing smooth portions arranged between the peripheral portions and disposed on the same radius therewith, a driven shaft disposed parallel to the driving shaft, a star wheel having circumferentially spaced eyelets fixed on the driven shaft and arranged so that the studs engage in the eyelets to rotate the star wheel and means on the star wheel and shaft providing alternating toothed and smooth portions complementary to the teeth on the sectors and the means providing smooth portions intermediate said sectors whereby an intermittent rotation is imparted to the driven shaft and means connected between the driven shaft and the carriage for translating the intermittent rotation of the driven shaft into an intermittent reciprocation of the carriage.
